UNITED STATES PATENT OFFICE

GRACE HUDSON, OF UKIAH, CALIFORNIA

DESIGN FOR A BOUDOIR DOLL

Application filed December 23, 1930. Serial No. 38,102. Term of patent 7 years.

To all whom it may concern:

Be it known that I, GRACE HUDSON, a citizen of the United States, residing at Ukiah, in the county of Mendocino and State of California, have invented a new, original, and ornamental Design for a Boudoir Doll, of which the following is a specification, reference being had to the accompanying drawing, forming part thereof.

The figure is a perspective view of a boudoir doll showing my new design.

I claim:

The ornamental design for a boudoir doll substantially as shown.

GRACE HUDSON.
